UNITED STATES PATENT OFFICE.

ALVIN O. CARMAN, OF POTTERVILLE, MICHIGAN.

SELF-BINDING HARVESTER.

SPECIFICATION forming part of Letters Patent No. 318,954, dated June 2, 1885.

Application filed August 15, 1883. (Model.)

To all whom it may concern:

Be it known that I, ALVIN O. CARMAN, of Potterville, in the county of Eaton and State of Michigan, have invented certain new and useful Improvements in Grain-Binding Harvesters; and I do hereby declare the following to be a full, clear, and exact description of the invention, such as will enable others skilled in the art to which it appertains to make and use the same.

My invention relates to an improvement in grain-binding harvesters, the object of the same being to provide a device wherein the mechanism for operating the tyer is situated above the platform, for the purpose of preventing the parts from being clogged by trash falling thereon. A further object is to provide simple and efficient means for imparting the necessary movements to the several parts of a grain-binding harvester; and with these ends in view my invention consists in the parts and combinations of parts as will be more fully explained, and pointed out in the claims.

In the accompanying drawings, Figure 1 is a view in front elevation of my improved harvester. Fig. 2 is a similar view showing the main driving-shaft in vertical section. Fig. 3 is a stubble-side view of the machine. Fig. 4 is a view in perspective from the opposite side. Fig. 5 is a plan view of the combined cam and mutilated-gear wheel and intermediate parts. Fig. 6 is a detached view of the combined cam-and-gear wheel. Fig. 7 is a detached view of the lever for operating the cord-guiding arm. Fig. 8 is a detached view of the lever for operating the cord tying and cutting mechanism, and Fig. 9 shows detached views of the compressor-arm shaft, sleeve, and crank.

A represents the frame of the machine, preferably rectangular in shape, and provided with suitable cutters and with the rollers B B', around which a canvas or other endless apron moves to deliver the grain to the binding mechanism, situated near one end of the frame. The rollers B and B' are suitably journaled to the machine-frame, and the roller B is provided, near one end, with a sprocket-wheel, C, around which the drive-chain D winds. This chain D passes upwardly and around the sprocket-wheel C' on the packer-shaft E, and drives the endless carrier simultaneously with

the movement of the packer-shaft. The packer-shaft E is journaled in the standard a and hanger a' considerably above the endless carrier, and is adapted to be provided with suitable packers for packing and holding the grain against the compressor-arm.

As before stated, one end of the packer-shaft E is provided with a sprocket-wheel, C', for transmitting its motion to the endless carrier, while the opposite end thereof is provided with a small pinion, b, through the intervention of which motion is imparted to the packer-shaft from the main shaft, which latter is situated below the packer-shaft in the same vertical plane therewith.

The main driving-shaft E' is connected by suitable couplings to the ground-wheel of the binder, so as to turn simultaneously therewith, and is journaled in the hangers a' and a''. Loosely journaled on this shaft between the hangers are the combined cam and mutilated-gear wheel F and the large pinion G. These wheels are free to revolve on the shaft independently thereof, and one is adapted for imparting the necessary movements to the knot-tying mechanism, compressor, and ejector, while the other moves the packer and endless apron. The cam-wheel F and pinion G are separated by the sleeve H, which latter is free to move longitudinally on the main shaft independently thereof, but is locked against independent rotation. This sleeve is provided at opposite ends with teeth e e', which latter are adapted to engage, respectively, the toothed hub d of the cam-wheel F and the toothed hub e of the large pinion, G. This sleeve is not long enough to engage the wheels F and G at the same time, and hence when one of the said wheels is in engagement with the sleeve the other is idle. The sleeve H is provided at or near its center with a collar, H', against the outer face of which the spiral spring I bears. The opposite end of this spring bears against the inner face of the pinion G, and the tendency thereof is to hold the sleeve in contact with the combined cam-and-gear wheel F, which latter moves the binding mechanism; but this tendency is overcome by mechanism, to be hereinafter described, which automatically shifts the sleeve over in contact with the pinion G, and holds it until the pressure of grain against the com-

pressor-arm is sufficient to release it. When the sleeve is in contact with the pinion G, the latter is revolved with the shaft and turns the pinion b^2 , which latter meshes with the pinion b on the packer-shaft, and consequently turns the latter simultaneously with the drive-shaft.

When the parts are in the position last mentioned, the packers are operated and the end-to-less apron moved toward the binding mechanism. As soon, however, as sufficient grain has been forced against the compressor-arm I' the pressure of the same against the said arm moves the arm outwardly and trips the sleeve H by means of the trip-bar Q, hereinafter described, and causes the sleeve to move in contact with the combined cam-and-gear wheel F. The wheel F is provided on its outer face with a cam-groove, J, preferably shaped substantially as shown, and is adapted to operate the cord-guiding arm K, which is attached to a shaft, N^4 , journaled in the cross-pieces g^4 h^4 to one side of the knot-tyer shaft. Portions of the cam-groove J on diametrically-opposite sides of the main shaft E' are formed concentric with the shaft, while the continuations or intermediate portions of the groove run eccentrically to the said shaft. One of the concentric portions of the groove is situated near the periphery of the wheel F and the other near the center thereof, and when the wheel is turned so that the anti-friction roller i rests in the outer concentric portion of the groove the cord-guiding arm stands away from or to the inner side of the knot-tyer, and when the roller i rests in the inner concentric portion of the groove J the cord-guiding arm K rests under or slightly outside of the knot-tyer. When the roller i rests within either of the concentric portions of the groove, the cord-guiding arm K remains at rest; but just as soon as the roller enters either of the eccentric portions of the groove the arm begins to move.

The anti-friction roller i, above referred to, is journaled to a stud, i' , Fig. 7, on the lever M, one end of which is pivotally secured in any desired manner to the machine-frame. This lever passes over the outer face of the combined cam-and-gear wheel F, and the outer end thereof is loosely connected to the lower end of the link N, the upper end of the link being loosely secured to the outer end of the bell-crank lever N'. This bell-crank lever N' is pivoted at its elbow to the machine-frame, and is connected at its lower end to one end of the connecting-rod N², the opposite end of which latter is connected to the crank N³ of the cord-guiding arm-shaft N⁴. Thus it will be seen that when the combined cam-and-gear wheel F is turned in the proper direction the lever M is vibrated, and through the intervention of the rod N², bell-crank N', and link N rocks the cord-guiding arm K. The combined cam-and-gear wheel F is also provided on its outer face with the ears or lugs g, in which the lever P is pivotally secured. This lever is

provided near its pivoted end to the inside of the collar on the movable sleeve H with an arm, h, having an anti-friction roller, h', pivoted thereto, which latter bears against the inner face of the collar H'. The outer free end of the lever P is adapted to engage with the trip-bar Q, which latter is rigidly secured to the sleeve R, to which the compressor-arm I' and the ejector S are secured. The trip-bar Q is bent, as shown, and the upper free end thereof is curved, so as to partly embrace the sleeve H on the main driving-shaft E' and extend over the lever P, as hereinafter described. Suppose, for the sake of illustration, that a bundle has been bound and ejected and the compressor-arm I' brought up to its vertical position to act as an abutment for the grain. As the compressor-arm rises the trip-bar Q is also moved toward the drive-shaft, and as the lever P, which is secured to the wheel F, the said lever comes up under the curved end of the trip-bar during the revolution of the combined cam-and-gear wheel F, the said curved end thereof engages with the free end of the lever P and holds the same. The wheel F, being in engagement with the toothed end c of the sleeve H, continues to move for a slight distance, which slight movement forces the anti-friction roller h' on the lever P against the collar H' and moves the sleeve over in contact with the large pinion G, where it remains until the packers and endless conveyer, which are now brought into operation, deliver a sufficient quantity of grain to the compressor-arm. When a sufficient quantity of cut grain has been forced against the compressor-arm I', the pressure of the same against the said arm tilts the latter outwardly, which movement turns the sleeve R, and the latter in turn moves the trip-bar Q outwardly away from the lever P. As soon as the lever is released the spring I forces the sleeve H into engagement with the combined cam-and-gear wheel F, thereby discontinuing the movement of the packers and imparting motion to the tying mechanism. When the sleeve H is moved toward the pinion G by the trip-lever, the teeth of the sleeve ordinarily engage the teeth of the pinion G and are disengaged from the teeth of the combined cam-and-gear wheel F; but the pinion G may stand in such position that the points of the teeth of the sleeve may strike the points of the teeth on the hub of the pinion G instead of entering between them, and as the sleeve must move toward the pinion upon a complete revolution of the combined cam-and-gear wheel F as it is forced over by the lever P, as before explained, it follows that some of the parts must necessarily yield to prevent damage to the machine. To prevent the difficulty from arising I have introduced the spring H⁵ between the pinion G and the depending hanger a², so as to enable the pinion to give or yield, if necessity demands. This spring is slightly stronger than the spring which moves the sleeve H, and hence, after the spring H⁵ has yielded sufficiently to enable the sleeve

H to be disengaged from the wheel F, it overcomes the pressure of the other spring and forces the pinion back to its original position. The hub d of the combined cam-and-gear wheel passes through the hanger a' , and is provided outside of said hanger with a crank T , to which the upper end of the pitman T' is connected. This pitman is connected at its lower end to the crank T^3 , rigidly secured to the needle-shaft T^4 , which latter is journaled to the machine-frame below the platform and parallel with the compressor-arm shaft I^4 . The needle-shaft and the compressor-arm shaft are geared together by the pinions g' , which latter cause the shafts to move simultaneously in opposite direction. The needle or binder arm T^5 is curved, as shown, and is adapted to rest under the platform or table while the grain is being delivered to the binding-table, and rise up and carry the cord over the bundle when the pressure against the compressor-arm is sufficient to move the trip-bar. The compressor-arm, being rigidly secured to a sleeve, R, which latter is loosely mounted on the compressor-arm shaft, does not fall outwardly when the needle rises, but retains its vertical position until after the bundle has been tied.

R' is a crank loosely mounted on the sleeve R and connected at its upper end to the lower end of the curved pitman R². This pitman extends diagonally upward and is connected at its upper end to the crank R³, the shaft of which latter is provided with a pinion, j , adapted to engage the segment U of the combined cam-and-gear wheel F, and with a shoe U' adapted to bear against the smooth portion of the periphery of the combined cam-and-gear wheel F, for the purpose of holding the pinion and crank locked against movement, while the pinion j is out of engagement with the segment-gear. The combined cam-and-gear wheel F is adapted to operate mechanism for compressing, tying, and ejecting a bundle of grain during one revolution, and the segment U is provided with sufficient teeth to turn the pinion once only, which revolution is sufficient to operate the mechanism for ejecting the bundle and elevating the compressor-arm.

As before stated, the crank R' is loosely mounted on the sleeve R, and is provided on one side with a groove, l , in which an outwardly-projecting stud, l' , of the sleeve R rests. This groove allows a certain limited movement of the sleeve independent of the crank R', but is held against unnecessary movement by the spiral spring V, one end of which is rigidly secured to the sleeve R, while the other is secured to the crank or to the machine-frame. This spring V tends to hold the compressor-arm in a vertical position, and when the crank R' is moved by the pitman R² one of the end walls of the groove l in the crank strikes against the stud l' of the sleeve R, and turns the latter until the ejector S has assumed

a vertical position and the compressor-arm I' a horizontal position. The crank R' is then turned back to its original position by the movement of the pinion, and the sleeve R, with its compressor I' and ejector S, moved back to their normal positions by the spring V.

The compressor-arm shaft I⁴ is provided with the rigid finger W, which latter rests immediately under the compressor-arm I', and is adapted to engage therewith as the needle T⁵ rises, for the purpose of forcing the compressor-arm inwardly against the grain, and to prevent the said arm from yielding while the grain is being compressed. This finger is made of metal, and being rigidly secured to the compressor-arm shaft I' only moves when the shaft is moved.

In this application I merely show the location of the knot-tying cord holding and cutting mechanism, without describing any particular construction thereof, as I can employ the devices shown in my Patent No. 269,826, bearing date January 4, 1883; or the device shown in my application filed May 3, Serial No. 93,800, or any other construction that will coact with the parts herein shown. This tying, holding, and cutting mechanism is located above the needle or binder-arm T⁵, and the knotted-shaft X, as in the patent and application before referred to, is provided with a small pinion, m , with which the pinion m' on the shaft Y meshes. This shaft is suitably journaled on the machine-frame, and is provided on its outer end with a small pinion, j' , adapted to be revolved once by the segment-gear of the combined cam-and-gear wheel F, and with a shoe, U', adapted to hold the pinion locked against unnecessary movement. The cord holding and cutting mechanism, which can be of any suitable construction, and which, in the present instance, is represented by the slide Z, are situated above the tying-bill of the knotter and act in conjunction therewith. This mechanism is provided with an upwardly-curved finger, n , the free end of which is adapted to rest within the oblong slot n' of the bell-crank lever Z'. This bell-crank lever is pivoted to the machine-frame alongside of the tying mechanism, and the outer end of the horizontal arm thereof is pivotally secured to the link Z', the lower end of which is secured to the inner bent end of the lever Z'. The opposite end of this lever is fulcrumed to the machine-frame, and the outer bent end is vibrated by the cam-groove Z⁴, in which the anti-friction roller n^3 , journaled to the lever Z³, rests. The cam-groove Z⁴ is concentric with the axis of the combined cam-and-gear wheel F throughout a greater portion of its length, while the remaining portion thereof is formed to move the outer bent end of the lever Z³ up and down once only at each revolution of the combined cam-and-gear wheel F, and consequently through the intervention of the link Z² and bell-crank lever Z' move the slide Z (which, as before stated, represents the

cord cutting and holding mechanism) away from the combined cam-and-gear wheel F and back again.

The combined cam-and-gear wheel F, and consequently the parts operated thereby, are prevented from a backward movement by the spring-dog Z, which latter bears against the periphery of the said wheel. If, when the machine is started, the trip-bar Q is disengaged from the lever P, the wheel F will revolve once; but as the packers are not at work there will be no pressure against the compressor-arm I', and the sleeve will be shifted over to the large pinion G. This starts the packers and endless apron, which deliver the grain against the cord and compressor-arm I'. When a sufficient quantity of grain to produce the necessary pressure has been delivered to the compressor-arm, the latter is forced outwardly a short distance and disengages the trip-bar Q from the lever P, and allows the sleeve H to be moved over to the combined cam-and-gear wheel F. The motion of the apron or conveyer and packers is now discontinued, and the other parts operated by the wheel F begin to move. The needle and compressor-arm rise to a vertical position, the needle T carrying the cord around the bundle. The cord-guiding arm then moves inwardly toward the knotter and carries the cord within reach of the tying-bill, and the slide Z, which represents the cord holder and cutter, grasps the cord. The tying-bill then revolves and ties the cord in a similar manner to that described in the patent or application before referred to, and the slide Z then moves back to its normal position, cutting the cord and releasing the ends thereof. The needle T and compressor-arm I' then fall back to a horizontal position, and the ejector throws the bundle from off the machine. The packers and conveyers are now thrown into operation, and deliver the grain to the compressor-arm, as before described, and so on indefinitely.

Any suitable framing for supporting the parts above the platform or table, and any suitable connection between the ground-wheels and driving-shaft, can be employed.

This machine greatly simplifies the present construction of grain-binding harvesters, and can be manufactured at a comparatively small cost.

It is evident that numerous changes in the construction and relative arrangement of the several parts might be resorted to without departing from the spirit of my invention, and hence I would have it understood that I do not confine myself to the exact construction shown and described, but consider myself at liberty to make such changes and alterations as fairly fall within the spirit and scope of my invention.

Having fully described my invention, what I claim as new, and desire to secure by Letters Patent, is—

1. In a grain-binding harvester, the combination, with a main shaft, loose wheels mount-

ed thereon, and a longitudinally-sliding sleeve located between the wheels for alternately locking them to the main shaft, of a packer-shaft operated by one of said wheels, an endless conveyer operated by the packer-shaft, and tying mechanism operated by the other wheel.

2. The combination, with a main drive-shaft and a pinion and a combined cam-and-gear wheel loosely mounted thereon, and a sleeve situated between the pinion and cam-wheel and adapted to move longitudinally on the shaft independently thereof, of an endless conveyer and packer-shaft indirectly connected with the pinion, tying mechanism indirectly connected with the combined cam-and-gear wheel, and devices for automatically moving the sleeve, whereby the packer and conveyer and tying mechanism are operated alternately.

3. The combination, with the endless conveyer, packer-shaft, drive-chain, and pinion secured to the packer-shaft, of the drive-shaft, loose gear-wheel mounted thereon, devices for locking the gear-wheel to the shaft, and an intermediate pinion connecting the pinion on packer-shaft with the pinion on the drive-shaft.

4. The combination, with the main driving-shaft, the loose pinion, and the loose cam-and-gear wheel, the adjacent ends of the hubs of the said pinions and cam-wheel being provided with teeth, of a toothed sleeve, and means whereby the said sleeve is moved longitudinally by the pressure of grain against the compressor-arm.

5. The combination, with the main driving-shaft, the loose pinion, and the combined cam-and-gear wheel mounted thereon, the adjacent ends of the hubs of the pinion and cam-wheel being provided with teeth, of the sleeve having a collar, a spring for forcing the sleeve against the cam-wheel, a lever pivotally secured to the cam-wheel and provided with an anti-friction roller adapted to bear against the collar on the sleeve, the compressor-arm, and trip-bar, the latter adapted to engage the lever for the purpose of forcing the sleeve against the pinion.

6. The combination, with the main driving-shaft, pinion, and cam-wheel, of the sleeve, spring-lever pivoted to the cam-wheel and provided with an anti-friction roller which bears against the collar on the sleeve, and the curved trip-bar actuated by the compressor-arm and adapted to shift the sleeve from the cam to the pinion, and vice versa.

7. The combination, with the endless conveyer and packer-shaft and suitable tying mechanism, of the main driving-shaft, pinion, combined cam-and-gear wheel, the lever secured to the latter, sleeve, spring, and trip-bar, all of the above parts adapted to operate as described.

8. The combination, with the cam-wheel having the cam-groove J therein, of the lever M, link N, bell-crank lever N', connecting-rod N'', and the cord-guiding arm K.

9. The combination, with the needle and

needle-shaft, a compressor-arm shaft, compressor-arm yieldingly secured on said latter shaft, and intermeshing pinions secured to said shafts, of a main driving-shaft, a pinion 5 loosely connected to said shaft, a clutch for locking the pinion to the shaft, devices connecting the needle-shaft and pinion, an arm connected with the compressor-arm shaft, and devices operating in conjunction with said 10 arm for moving the clutch out of engagement with the pinion.

10. The combination, with the needle-shaft, the shaft I^4 , pinions connecting the said shafts, sleeve R , and compressor and ejector secured 15 to said sleeve, of the crank R' , pitman R^2 , pinion j , segment-gear U , stud on sleeve R , and spring V .

11. The combination, with the compressor-arm shaft, of the sleeve, compressor-arm, ejector, crank R' , pitman R^2 , pinion j , and spring V .

12. The combination, with the needle and compressor-arm, of the compressor-arm shaft having the rigid finger W thereon, for the purpose set forth.

25 13. The combination, with the compressor-arm, ejector, needle, and spring - actuated sleeve R , of the compressor-arm shaft having the finger thereon, substantially as set forth.

14. In a grain-binding harvester wherein the tying mechanism is situated above the 30 platform, the combination, with suitable packers for delivering the grain, a compressor-arm shaft, a compressor-arm yieldingly secured on said shaft, and tying mechanism, of a main or driving shaft, loose wheels thereon and operating 35 respectively the packing and tying mechanism, a clutch located between the wheels, and devices operated by the yielding compressor-arm for throwing the packing mechanism out of gear with the main or driving shaft.

15. The combination, with the compressor-arm, compressor-arm sleeve, and spring for holding the compressor-arm up in position, of the compressor-arm shaft and finger W , substantially as set forth.

In testimony whereof I have signed this specification in the presence of two subscribing witnesses.

ALVIN O. CARMAN.
